INVENTOR

Robert Barnes Shepherd,

UNITED STATES PATENT OFFICE.

ROBERT BARNES SHEPHERD, OF NEW YORK, N. Y.

DESIGN FOR A BRUSH-BACK.

SPECIFICATION forming part of Design No. 29,167, dated August 9, 1898.

Application filed May 12, 1898. Serial No. 680,517. Term of patent 14 years.

To all whom it may concern:

Be it known that I, ROBERT BARNES SHEPHERD, a citizen of the United States, residing in the city, county, and State of New York, have invented and produced a new and original Design for a Brush-Back, of which the following is a specification, wherein reference is made to the accompanying drawing, in which the figure is a perspective view of a brush whose back shows my design.

The leading feature of the design consists in a series of curved bars arranged so as to be parallel or concentric and having spaces

between, the curved bars being joined together by small bridging portions, as shown. 15 The whole, when viewed on the side opposite the bristles, presents the appearance of an open grid, as shown.

I claim—

The design for a brush-back as herein shown 20 and described.

ROBERT BARNES SHEPHERD.
